Patented Feb. 8, 1927.

UNITED STATES PATENT OFFICE.

HARRY H. HONIGBAUM, OF RICHMOND HILL, NEW YORK.

RETAINER.

Application filed July 10, 1926. Serial No. 121,512.

This invention is a new article of manufacture adapted to be used as a retainer in the various arts. For example, it may be used in the hanging of picture frames or other articles on walls or by varying the size or shape is well adapted for the securing of composition shingles to a roof. In fact, by variations in shape and size, the invention is susceptible to an infinite number of uses without departing from the spirit or scope of the invention.

In its broad aspect the invention comprises a body portion provided with one or more spikes or prongs formed integral with the body portion and stamped therefrom, said body portion and prongs being stamped from a blank, wherein the prongs are formed by stamping from the blank one or more portions thereof extending into the body of the blank from one or more of the edges of such blank. In every embodiment of the invention, the prong portion of the blank extends from one edge of the blank into the body of the blank and terminates within its edges. This manner of forming the retainer is believed to be broadly novel. Other portions of the blank are preferably bent or stamped into the form of one or more keepers of appropriate shape.

In practically carrying out the invention, sheet metal is stamped to form a blank and then by stamping and forming operations, each blank is manipulated into the form of a retainer with the prongs formed as described and one or more keepers are simultaneously stamped up in appropriate relation to the prongs to fulfill the function for which the retainer is constructed. The retainer of this invention is economical to manufacture, is not susceptible of a turning movement when in position and will efficiently retain articles on the wall, shingles on the roof and other devices in proper places.

Features of the invention, other than those specified, will be apparent from the herein-after detailed description and claims, when read in conjunction with the accompanying drawings.

The accompanying drawings illustrate different practical embodiments of the invention, but the constructions therein shown are to be understood as illustrative only, and not as defining the limits of the invention.

Figure 1 is a sheet metal blank from

which the retainer of Figure 2 may be formed.

Figure 2 is a retainer stamped from the blank of Figure 1; and,

Figures 3, 4, 5, and 6 are modified forms of retainer, all embodying the present invention.

Referring first to Figures 1 and 2, the former figure shows a rectilinear blank 1 which is adapted to be cut by suitable dies 65 along the lines 2, 2 to form a convergent or wedge shaped spike portion 3. It will be noted that the lines 2, 2 intersect at the free edge of the blank, so that the spike portion 3 extends from the edge 4 of the 70 blank into the body of such blank and terminates at a spaced distance from the opposite ends 5 of the blank. In other words, the spike portion extends into the blank and to a point remote from its edges. After 75 the blank has been cut along the lines 2, 2, it is bent along the line 6 to position the prong or spike 3 in angular relation to the remainder of the blank. In practice, the prong 3 may extend at right angular relation to the blank or in any other angular relation appropriate to the particular use to which the retainer is to be put. After bending the blank along the line 6 to form the spike 3, the blank is further bent along the 80 lines 7 to form keepers 8, 8, whereupon the retainer is complete. The keepers may manifestly be of any suitable shape, but the simplest form of retainer is shown in Figure 2.

It will be noted that the spike is widest at its base so that it is strongest at the point where it joins the body portion 9 of the retainer. Moreover, the body portion is substantially bifurcated by the cutting away of 95 the spike, but this bifurcation is produced by a tapering cut so that where the keepers are formed, the arms of the body portion are at substantially the widest. In other words, the keepers are formed at the point 100 where the body portion is the strongest and the body portion joins the spike where the spike is the strongest. These parts of the body portion between the keepers and the spike are, in practice, generally subjected 105 only to tension without any appreciable bending strain and it will therefore appear that the disposition of the metal is such as to give maximum strength for the material used.

90

100

105

110

The structure of Figure 3 differs from that of Figure 2 only in that an additional spike and an additional keeper are added. Thus, in this figure, 9^a is the body portion, 5 3^a, 3^b are the spikes and 8^a, 8^b and 8^c, are the keepers.

The structure of Figure 4 is practically the same so far as the spike portions are concerned as the structure of Figure 3, but 10 the keepers are formed from the body portion 9^b in a different manner. These keepers 8^b are stamped out of the body portion instead of being bent up from one edge thereof. The spike portions 3^b are formed 15 in the same manner as in Figure 3.

The structure of Figure 5 is, practically speaking, a duplication of the structure of Figure 2 joined end to end and positioned in angular relation to one another. Thus 20 the elongated body portion 9^c is provided at each end with keepers 8^c and between each two keepers a spike portion 3^c is stamped out.

In Figure 6, I have shown the invention 25 as constructed in the form of a picture hook to hang pictures from a picture molding. The body portion 9^d is formed at its lower end with two keepers 8^a, while at its opposite end, it is bent to form a single, curved 30 keeper 8^{dd}. This latter keeper is adapted to hook over a picture molding and the picture wire is adapted to engage with the keepers 8^a. The single prong 3^d stamped out from the body portion, as hereinbefore described, 35 is made relatively short and is adapted to be pressed into the wall to keep the device from shifting or swinging on the molding.

The several embodiments of the invention 40 shown in the drawings are only illustrative of a great number of structures which might be constructed in accordance with the present invention and the particular configuration of these several structures would, manifestly, depend upon the particular use to 45 which they are to be put in the several arts. For instance, the retainer of this invention may be employed to mount pictures, book frames, mirrors, etc. on a wall, or for attaching strip shingles to a roof or for holding 50 down individual shingles or roll roofing at the weather edge thereof or for numerous other purposes when the invention is made in the smaller sizes. If the device is made in larger sizes, it may be used for various 55 other purposes, for hat racks, coat racks and other analogous uses wherein, manifestly, the keeper will be formed of a shape appropriate to the particular use to which the device is adapted. It is obviously not practical 60 to show all forms of which the invention is susceptible and the accompanying drawings are merely illustrative. For these

reasons, the invention is to be understood as fully commensurate with the appended claims.

The invention also resides in the method 65 of manipulating the blank in the form of a retainer as described.

Having thus fully described the invention, which I claim as new and desire to 70 secure by Letters Patent is:

1. The herein described method of making a retainer which consists in providing a sheet metal blank with divergent slits intersecting one another at one edge of the blank 75 and extending at a sharp acute angle into the body of the blank, thereafter bending that portion of the blank between the slits into angular relation with the body of the blank to form a spike portion, and thereafter bending another portion of the blank back upon itself and substantially parallel with the body portion to form at least one keeper at an outer edge of the body portion.

2. As a new article of manufacture, a 85 sheet metal body portion having a spike integral therewith and extending from a point in the body portion inwardly from the edges of the body portion and in angular relation to the body portion, said body 90 portion being provided with a slot extending from the base of the spike to one edge of the body portion, and at least one keeper integral with the body portion and bent toward the latter at an edge thereof said 95 keeper extending substantially parallel with the face of the body portion.

3. As an improved article of manufacture, 100 a retainer composed of a single piece of sheet metal and embodying a body portion provided inwardly of its edges with a spike positioned at angular relation to the said body portion, the body portion being provided with an angular slot formed by the production of said spike, and angled keepers 105 bent at an angle to the body portion with their terminals parallel with and in relative close proximity to the outer edges of the body portion.

4. As an improved article of manufacture 110 a retainer formed of a single piece of sheet material with divergent slits intersecting one another at one edge of the body portion, a spike bent from the body portion at the base of the angle formed by said slits, and 115 keepers formed by free portions at the side edges of the body portion, bent at an angle to the body portion and again substantially parallel to such edges.

In testimony whereof, HARRY H. HONIGBAUM has signed his name to this specification this 30th day of June, 1926.

HARRY H. HONIGBAUM.
